(57) **CLAIM**

The ornamental design for a pet feeding device, as shown and described.

DESCRIPTION

FIG. 1 is a top, first side, and front perspective view of a pet feeding device embodying the new design;
 FIG. 2 is a bottom, second side, and back perspective view thereof;

FIG. 3 is a top view thereof;

FIG. 4 is a bottom view thereof;

FIG. 5 is a first side view thereof;

FIG. 6 is a second side view thereof;

FIG. 7 is a back view thereof; and,

FIG. 8 is a front view thereof.

The uniform repeating broken lines depict portions of a pet feeding device in which the claimed design is embodied and form no part of the claimed design.
